UNITED STATES PATENT OFFICE.

ALBERT J. DREHER AND FORREST J. COUCH, OF CINCINNATI, OHIO, ASSIGNORS TO THE AMERICAN LAUNDRY MACHINERY COMPANY, OF NORWOOD STATION, CINCINNATI, OHIO, A CORPORATION OF OHIO.

CENTRIFUGAL STARCHING APPARATUS.

Application filed September 14, 1925. Serial No. 56,254.

This invention relates to improvements in apparatus for starching laundry.

In the laundrying of clothes it has heretofore been the practice after washing the clothes to treat them in an extractor, remove the same from the extractor and place them in a tank or tub for starching. Such a process is not only slow and cumbersome, but difficulty has also been experienced in maintaining the proper degree of thickness of the starch solution which is thinned out by the moisture still retained by the laundry after the extracting process. Furthermore, the clothes according to the old process are not uniformly starched, with the result that after being ironed there will appear glossy spots on the same.

It is therefore the object of the present invention to perform the starching operation in the same container which is used for extracting. That is to say, according to the present improved apparatus, after performing the extracting operation the starching solution is supplied to the same basket which contains the clothes, and by rotation of the basket the clothes are starched uniformly throughout.

It is a further object of this invention to provide a starching apparatus in which the starch is sprayed onto the clothes from a point outside of the basket or container.

It is a further object to provide a circulating system of pipes and a pump for forcing the starch solution therethrough so as to be sprayed onto the clothes and returned for recirculation.

Another object of this invention is to provide means for thickening the starch solution as it is being circulated through the system of pipes and without stopping the starching operation.

It is likewise an object of this invention to provide a starching apparatus in which the starch cooker consists of a separate container which may be cut off from the rest of the device during the starching operation except as it may be desired by the operator to admit the comparatively thick starch solution from the starcher to the circulating system so as to correct the dilution of the starch solution which may be caused by the moisture remaining in the clothes after the extracting operation.

It is a further object of this invention to provide a system of pipes through which the starch solution is circulated and which is so

arranged as to comprise a standpipe which will collect and hold sufficient starch solution for priming the pump which is also embraced within the circulating system.

A further object is to provide means for flushing and cleaning the starch cooker as well as the rest of the starching apparatus, the connections being so arranged that the different parts may be separately cleaned and the water drained therefrom.

Other objects will appear from the following description and claims when considered together with the accompanying drawings.

Fig. 1 is a front elevation of our improved starching apparatus with parts broken away and shown in section; Fig. 2 is a plan view; Fig. 3 is a horizontal section taken on line 3—3, Fig. 1; Fig. 4 is a detail view of the injector valve; Fig. 5 is a plan view of the water inlet with a part broken away; Fig. 6 is a detail view of the spraying nozzle partly in section; and Fig. 7 is an end view of the nozzle.

Within the curb 1 there is mounted the basket 2 which is adapted to be rotated by means of the belt 3 which extends about the fly wheel on the lower end of the basket spindle 4. The belt 3 is driven by the motor 5. The curb 1 is provided with the drain pipe 6 which has the valve 7. Upon the top of the curb 1 there is hinged the cover 8, through which extends the spraying nozzle 9 which is thus located at a point above and outside of the basket 2. This nozzle 9 is so arranged and directed in its discharge that the starch solution will be sprayed therefrom onto the clothes contained within the basket as the same is rotated. The nozzle 9 comprises the needle valve 10 which is adapted to be opened

and closed by means of the handle 11 at the other end thereof, this needle being threaded in the shank 12 of the pipe 13 through which the starch solution is fed. The bracket arm 14 of hinge 15 of the cover 8 surrounds the pipe or conduit 13 and is secured thereto by means of the strap 14^a. The hinge 15 has extending through the rear ends thereof the pintle rod 16 which is mounted in the straps 17 so as to permit the cover to be opened and closed. There is provided also a joint or union member 18 for connecting the sections of pipe 13, this union member having an extension which receives the projecting end of pintle rod 16, as clearly indicated in Fig. 2.

Thus, with the stuffing box connection 19 in the one section of the pipe 13, it is possible for the other section of pipe 13 to be raised and lowered with the cover. In other words, the 5 cover may be raised and lowered without being hindered by the particular pipe arrangement. Also, by removing strap 14^a, the pipe and nozzle can be raised independently of the cover.

- 10 A vertical section of pipe 20 extends downwardly from the pipe 13 and connects with the horizontally disposed pipe section 21 which affords communication with the pump 22 and has connection at its other end with 15 the lower end of the standpipe 23 projecting from the bottom of the curb channel. The pump 22 is driven by means of the gear 24 meshing with the pinion 25 which in turn is mounted on the shaft of the motor 26. 20 The pipe section 21 is connected with a short section of pipe 27 which communicates with the horizontally disposed pipe section 28 which in turn connects with the short pipe section 29. The other end of pipe 29 is in 25 communication with the outlet pipe 30 of the starch cooker 31. The pipe 28 is provided with the valve 32 which controls the supply of cooked starch solution from the cooker 31 to and through the circulating system just 30 now outlined and described for spraying the starch solution onto the clothes in the container or basket 2.

The cooker 31 is provided with a cover 33 and has the steam manifold 34 suitably 35 mounted upon the side thereof for communication with the inside of the cooker for cooking the starch.

As a means of injecting comparatively thick starch solution from the cooker to the pipe 40 20 of the circulating system, we have provided the injector 35 which communicates at its one end with the pipe 20 and at its other end with the pipe 36 which has direct connection with the pipe 30 at the lower end of the 45 starch cooker. This injector is controlled by means of the valve 37, and when this valve is open, the starch solution from the cooker will be drawn by injection into the pipe 20 through which the comparatively 50 thin starch solution is being circulated during the starching operation.

The operation of our improved device as thus far described is briefly stated as follows. With all of the valves closed, the extracting 55 operation having been already performed, and the water drained from the curb through the discharge pipe 6 during the extracting operation, the clothes are then in condition for the starching operation. During the extracting operation the pump 22 has been idle. Likewise the extractor basket is idle after the extracting operation has been performed and until the starch solution is fed into the circulating system for the starching operation. Upon opening the valve 32 and start-

ing the pump 22, the starch solution from the cooker will be drawn out through the discharge 70 30, through the pipes 29 and 28, the pipe 27, through the pump, up through the pipe 20 to the pipe 13 and through the spraying nozzle 9 onto the clothes. During the starching operation, with the basket 2 in rotation, the starch solution will be thoroughly and uniformly applied to the clothes and any excess of starch solution will return 75 through the pipe 23. As soon as the pipe 23 contains a sufficient amount of starch solution to properly prime the pump 22, the valve 32 is closed and this starch solution is then circulated and re-circulated throughout 80 the system of pipes just now referred to. Whenever the operator deems it advisable to thicken the starch solution after it has passed and re-passed through the basket in which the clothes are contained, it is merely necessary to open the injector valve 37 so as to permit the necessary quantity of comparatively thick starch solution to enter through the outlet 30 and the pipe 36 up through the injector connection to the pipe 20. As soon 85 as a sufficient quantity has been injected into the circulating system, the valve 37 is closed.

Upon completion of a starching operation, the pump motor and basket operating motor are both stopped. Then upon again starting the pump motor, there will be sufficient starch solution in the pipe 23 to prime the pump; so that it is only necessary to open valve 32 at the beginning of the operation to 90 prime the pump.

When at the end of the day's work it is desired to drain and flush out the entire apparatus, this may be done by first draining the remaining starch solution from the 105 cooker 31 through the discharge valve 38. Likewise the valve 7 may be opened to drain the bottom of the curb 1. Then, by opening valve 39 which controls the water inlet manifold 40, water can be admitted to the pipes 110 and forced therethrough by means of the pump for cleaning the same. This pipe 40 has communication with both the pipes 28 and 36, as clearly indicated in the drawings.

As soon as a sufficient quantity of water has been admitted to the system for cleaning the same, this valve 39 will be closed. During admission of the water to the system of pipes, as just now referred to, a certain quantity of water will of course back up through the discharge outlet 30 into the bottom of the cooker 31 because of the direct connection of the manifold 40 with the pipe 36 and the outlet 30. Likewise water will stand in the pipes 28 and 36, and upon operation of the pump 22 it will be forced through the same system of pipes as just now described as constituting the path of circulation for the starch solution during the starching operation. That is to say, with both the injector 125 130

valve 37 and the spraying valve 10 in open position, the water will be forced up through the pipe 20, through the pipe sections 13, through the spraying nozzle 9 into the basket 2 and down through the pipe 23 and the pipe 21 to the pump 22. Upon completion of this flushing operation, and upon closing the valves 10 and 37 and opening the valve 45, the water will be discharged into the starch 10 cooker. Then upon closing valve 45 and opening the valve 41, the wash water is discharged through pipe 42 to a drain. When water no longer flows from the drain, clean 15 water is admitted through valve 39 and pumped up through pipe 20 so as to flush the same. This can be repeated if desired and pipe 20 can be drained by removing plug 46. Pipe 23 can be drained by removing plug 47.

20 Thus we have provided not only a starching device in which we utilize as part thereof the same extractor which has been used for the extracting operation, but we have also provided a device in which the clothes are thoroughly and uniformly starched and in which there is no danger of the starch solution clogging as it is fed to the clothes. We have provided also a device in which the tendency for the starch solution to become thinned out, 25 due to the remaining moisture in the clothes after the extracting operation, may be corrected by admitting from the starch cooker a certain quantity of the comparatively thick starch solution. Thus in our improved device, the solution of starch in the cooker is maintained independent and separate from the system of pipes through which the starch solution is circulated during the starching operation, and is not subjected to the thinning effect of the moisture retained by the 30 clothes in the extracting basket.

Furthermore, we have provided a device in which the pump may be readily primed due to the particular arrangement of the pump 45 and the pipes with respect to each other.

Furthermore, we have provided an improved system whereby the different parts of apparatus may be readily and thoroughly cleaned after the starching operation, and one 50 in which the surplus starch solution at the end of the day's work may be saved.

Other advantages resulting from our improved apparatus will be obvious to those who are skilled in the art to which this invention relates.

What we claim is:

1. Apparatus of the character described, comprising a centrifugal extracting machine, a starch solution storage reservoir, conduit means through which starch solution may be circulated through said machine, fluid supply means for flushing purposes, and delivery connections between said fluid supply means and said conduit means and between said fluid supply means and said starch solution storage reservoir, whereby said conduit means and said storage reservoir may be flushed by fluid from said fluid supply means. 60

2. Starching apparatus, comprising a centrifugal extractor provided with a rotatable basket and a curb having a waste drain outlet, a starch reservoir, a circulating pump having its suction side provided with valved connections to said curb and reservoir for conducting material therefrom to the pump and its discharge side connected to a supply conduit for the extractor, said conduit having a nozzle located to distribute the supply over material in the basket, whereby starch solution may be circulated from the curb to the pump and then returned to the extractor through said supply conduit, and starch solution may be drawn from said reservoir to prime the pump. 70

3. Starching apparatus, comprising a centrifugal extractor provided with a rotatable basket and a curb having a waste drain outlet, a starch reservoir, a circulating pump having its suction side provided with valved connections to said curb and reservoir for conducting material therefrom to the pump and its discharge side connected to a supply conduit for the extractor, said conduit having a nozzle located to distribute the supply over material in the basket, whereby starch solution may be circulated from the curb to the pump and then returned to the extractor through said supply conduit and starch solution may be drawn from said reservoir to prime the pump, and a separate valved connection from said reservoir to said extractor supply conduit, whereby additional starch from the reservoir may be introduced into the stream circulated by the pump from the curb to the extractor basket. 80

100 In testimony whereof we hereby affix our signatures.

ALBERT J. DREHER.
FORREST J. COUCH.
